UNITED STATES PATENT OFFICE.

JOSEPH D. FARKAS, OF BROOKLYN, NEW YORK.

FOOT-BALL COVER.

1,162,591.

Specification of Letters Patent.

Patented Nov. 30, 1915.

Application filed August 23, 1915. Serial No. 46,901.

To all whom it may concern:

Be it known that I, JOSEPH D. FARKAS, a citizen of the United States, residing at Brooklyn, in the county of Kings and State 5 of New York, have invented certain new and useful Improvements in Foot-Ball Covers; and I do hereby declare the following to be a full, clear, and exact description of the invention, such as will enable others skilled 10 in the art to which it appertains to make and use the same.

This invention relates to sporting goods and more particularly to foot ball or basket ball covers.

15 It has for an object to provide a more economical construction for a cover and for a simplified assembling of the parts thereof.

20 A further object of this invention is to provide a fabric cover having a protective flap for the bladder formed integral in one of the sections comprising the cover.

Further objects will be apparent from the following specification, appended claims and drawing, in which—

25 Figure 1 shows in plan view, two of the similar sections used in making the cover, Fig. 2 is a similar view of another of the sections, Fig. 3 is a similar view of another of the sections, Fig. 4 is a perspective view 30 of the section shown in Fig. 2 in a finished state, Fig. 5 is a perspective view of the section shown in Fig. 3, having the tab secured in place thereon, Fig. 6 is a plan view showing the sections assembled and ready to be 35 turned inside out as in the finished product, and Fig. 7 is a cross sectional view showing the completed article.

This invention permits the formation of a cheap but economical foot ball or the like 40 in providing for a simplified form of a cover which in the finished product is intended to receive a toy rubber balloon in common use on the market.

45 Referring to the drawing in which the evolution of assembling the several parts will be clearly described, there are shown the four sections which comprise a cover as at 10, 11, 12 and 13 of which the sections 10 and 11 are similar and of substantially elliptical form in outline. The section 12 has a tongue 14 formed thereon which is subsequently folded along the line 15 and then stitched along the lines 16 and 17 which coincide when the tongue is folded over as 55 shown in Fig. 4 and when said tongue has been securely held in folded position, a se-

ries of eyelets 18 is formed through the tongue and body portion of the section 12. The section 13 has a tongue 19 in which an opening 20 is formed to receive the neck of 60 the bladder as will be described, and this tongue is intended to be folded along the line 21 to cause the lines 22 and 23 to coincide so that stitching through these lines will securely hold the tongue as shown in 65 Fig. 5 and allow the flap 24 to extend beyond the line of stitching. When the tongue 19 has been securely stitched, a series of eyelets 23 is formed through the tongue 19 and body portion of the section 13 and these eyelets coöperate with the eyelets 18 to receive 70 a closing means such as a string to effectively close the opening subsequently formed by the edges 15 and 21.

When the section 12 has been completed 75 to the form shown in Fig. 4, it is stitched to one edge of the section 10 in having the usual stitching pass through the line 25 of the section 10 and the line 26 of the section 12, and likewise the sections 11 and 13 are 80 secured to one another in having the stitching pass through the lines 27 in the section 11 and the line 28 in the section 13. This forms the two halves of the cover which are subsequently secured to each other as shown 85 in Fig. 6 in having the sections 12 and 13 secured to each as along the lines 29 and 30 and in having the stitching continuous from the lines 29 and 30 to include and attach the sections 10 and 11 as through the lines 90 31 and 32. This stitching will preferably be done by starting at the point 33 to one side of the opening formed by the folded portions 15 and 21 as indicated as at 33 and then continuing along the line 30 to and including 95 the line 32 to the line 30 on the opposite side of the opening where it terminates at the opposite point 33. In stitching the marginal edges, the meeting edges between the sections 10 and 12 and 11 and 13 are folded 100 over in one direction as shown at 34 and in the opposite direction as shown at 35.

Upon the completion of these operations, the cover member is finished but requires being turned inside out through the opening 105 formed by the free edges 15 and 21 and after that has been done, a bladder 36 such as in common use for toy balloons is inserted through the opening and has its neck 37 protrude through the opening 20 when said 110 bladder may be inflated. The neck 37 is then twisted a number of times to form a

seal and is then tucked under one or the other of the tongues 19 or 14. The tongue 24 serves as a closure for the opening formed by the edges 15 and 21 to prevent the bladder 36 from extending therethrough, and after the bladder has been inflated and the neck 37 properly twisted and placed, the lacing 38 which passes through the eyelets 18 and 23 may be tightened and tied.

10 It is thought that the features of novelty in this application are clearly defined over the former state of the art and that further description is unnecessary.

Having thus described my invention, I 15 claim:

1. In a cover for foot balls and the like, a plurality of sections, tongues formed on some of said sections, said tongues being foldable over said sections, stitching secur-

ing said tongues to said sections, eyelets 20 formed in said tongues and sections lying thereunder, a flap extending from one of said tongues beyond the stitching and said flap having an opening formed therein.

2. In a cover for foot balls and the like, 25 a plurality of sections, tongues formed on some of said sections, said tongues being foldable over said sections, said sections being stitched together except for a portion thereof along the edges formed by said 30 tongues, eyelets formed in said edges formed by said tongues, and a tab having an opening therein formed by one of said tongues to serve as a closure for an opening formed by 35 the meeting edges of said sections formed by said tongues.

In testimony whereof I affix my signature.

JOSEPH D. FARKAS
